UNITED STATES PATENT OFFICE.

WILLIAM E. CLOUGH, OF REDONDO BEACH, CALIFORNIA.

HAND AND FOOT ACCELERATOR FOR CARBURETERS OF AUTOMOBILE ENGINES.

1,398,625.

Specification of Letters Patent. Patented Nov. 29, 1921.

Application filed June 21, 1919. Serial No. 307,209.

To all whom it may concern:

Be it known that I, WILLIAM E. CLOUGH, a citizen of the United States, residing at Redondo Beach, in the county of Los Angeles and State of California, have invented 5 a new and useful Hand and Foot Accelerator for Carbureters of Automobile Engines.

This invention relates to accelerator operating means and it may be said to consist 10 of new and useful features and in improved construction, combination and arrangement of parts and will be described as embodied in the preferred form of apparatus herein shown.

15 The invention comprises an accelerator operating means that can be actuated by both the hand and foot or by either in one direction to open the throttle valve; and automatic means are provided for moving the 20 mechanism in the opposite direction to close the valve.

Another feature of the invention is shown in the means for adjusting the parts to fully open or close the throttle valve.

25 Objects of the invention are simplicity of construction, effectiveness in its operation; and ease of installation on automobiles already in operation.

In carrying out this invention a foot lever 30 is connected to the usual throttle lever in common use so that either pressure of the foot or pressure of the hand may be used to affiliate the engine.

An advantage of this invention is that 35 control of the engine is insured under practically all driving conditions; and this is effected by a slight change of present constructions.

Other objects, advantages and features of 40 the invention may appear from the accompanying drawings, the subjoined detailed description and the appended claims.

The drawings illustrate the invention.

Figure 1 is a side elevation of the apparatus attached to the engine and foot board of 45 an automobile; parts broken away and parts shown by dotted lines.

Fig. 2 is a section on the line α^2 of Fig. 1, parts omitted and broken away and an altered 50 position of parts shown by dotted lines. Also parts are diagrammatically shown.

Fig. 3 is a side elevation of the left hand part of what is shown in Fig. 2.

Fig. 4 is a section on the line α^4 of Fig. 3; 55 and also showing by dotted lines an altered position of parts.

Fig. 5 is a section through the stop lug that is adjustably secured to the cable, drawn to a full size scale.

Fig. 6 is a section through the foot board 60 of an automobile and showing in side elevation the foot lever for actuating throttle valve; also showing by dotted lines an altered position of the lever.

Fig. 7 is a plan elevation of what is shown in Fig. 6.

Fig. 8 is a section on the line α^8 of Fig. 6 65 with the parts shown full size.

In detail the engine 1, steering post 2 and 70 foot board 3 shown by dotted lines in Fig. 1 are old and well understood; and a detailed description of them is not given; also the carbureter 4 that is attached to the engine manifold 5 can be of any type.

75 As is well known the throttle valve 6 of the carbureter is provided with a throttle lever 7 which lever has heretofore been connected by a rod to a finger 8 that is secured to the bottom end of a rod 9 that is attached 80 to the steering post 2 of the automobile and which has on the upper end thereof the hand lever 10, by which means the throttle valve has been opened and closed.

In applying this invention the usual rod 85 connecting the throttle lever 7 with the finger 8 is eliminated and in its place there is substituted a flexible connection shown as a cable 11 which has one end attached to the throttle lever 7.

90 This cable 11 has its other end passed through the pulley block 12 and over the pulley 13; which pulley is loosely mounted on the end of the finger 8. That is, the block 12 has attached thereto one end of the stud 95 14, which bolt passes through an opening 15 in the end of the finger 8; and is attached thereto by the nut 16.

From the pulley 13 the cable 11 extends 100 through a slot 17 in the foot board 3 and is attached to one end of the foot lever 18.

The lever 18 has at its forward end the lugs 19 that are spaced apart a sufficient distance to permit the insertion of the cable 11

which cable has its end looped about the bolt 20 which bolt when tightened grips the cable between the lugs 19.

The center portion of the lever 18 has 5 therein the bearing 21 for the cotter pin 22; which cotter pin also passes through the upward extending lugs 23 of the bracket 24.

The bracket 24 has its base secured to the foot board 3 by the screws 25; so that it is 10 easily attached or detached.

There is adjustably mounted on the cable 11 a lug 26 which lug has therein the set screw 27 by which screw the lug is secured to the cable in any predetermined place; and as seen in Fig. 2 this lug is secured to the cable 11 so that the lug contacts with the pulley 13 when the throttle valve 6 is closed; and the lug is held in contacting engagement with the pulley by means of the tension 20 of the spring 28 which spring has one end attached to the throttle lever 7 and the other end attached to the screw 29 on the engine 1, see Fig. 1.

Assuming that the hand lever 10 is in frictional contact with the sector plate 30 so that it holds the finger 8 rigidly in the position shown by full line in Fig. 2, the throttle valve will be closed and the lug 26 contacting with the pulley 13.

30 With the parts in this position and the foot lever actuated the finger 8 will remain stationary holding the pulley block 12 in a fixed position while the cable 11 moves over the pulley 13 to move the lever 7 and open 35 the throttle valve. In other words when foot pressure is applied to the rear end 31 of the foot lever 18 and it is moved from the full to the dotted line position shown in Fig. 6 the cable 11 will be moved in the direction of the arrow 2 shown in Figs. 2 and 4, which movement of the cable will move the throttle valve 7 against the tension of the spring 28 which movement will open the throttle.

45 Or if desired the lever 10 can be actuated by the hand to move the finger 8 from the full to the dotted line position shown in Fig. 2 which movement will also move the lever 7 to open the throttle valve; and as 50 the movement of the throttle lever 7 to open the throttle valve is against the tension of the spring 28 it is obvious that the spring will close the throttle valve when the finger 8 is moved in the reverse direction.

55 From the foregoing it can readily be seen that the throttle valve is under control and easily operated by either the hand or foot; also it is obvious that the throttle valve can be partly opened by the hand lever for running the engine at medium or low speed and accelerated by the foot lever for high speed. That is if the hand lever 10 is actuated to move the finger 8 from the full line position shown in Fig. 4 to the line A—A or 60 about forty five degrees the throttle valve

will be about half open; and owing to the frictional contact of the lever 10 with the sector bar 30 it will remain in that position, and the engine will run at a reduced speed. When it is desired to increase the 70 speed the throttle valve is additionally opened by a light pressure of the foot on the foot lever.

With this arrangement and combination 75 of parts the change of engine speed can be more quickly and easily accomplished than by moving the throttle by hand; the advantages of which will be obvious to those accustomed to driving cars in crowded cities 80 where traffic regulation requires that drivers of vehicles start quickly on signal.

It is also quite obvious that the lever 10 can be actuated to open the throttle valve any desired degree and held in that position by means of the sector plate 30; and that the foot lever can be used to coöperate with the hand lever in any of the changed positions.

Also attention is called to the simplicity of the apparatus in construction, installation and operation.

The flexible connection or cable between the throttle lever 7 and the foot lever 18 may be of any suitable flexible material that will move over the periphery of the pulley 13. 95

I claim.

1. In a hand and foot accelerator, a throttle lever, a cable one end of which is attached to said throttle lever, a foot lever for moving said cable to actuate the throttle 100 lever, and the other end of said cable being attached to said foot lever, a lug mounted on said cable, a hand lever, and means on said hand lever to engage said lug to actuate the throttle lever.

2. In a hand and foot accelerator, a throttle lever, a flexible connection having one end attached to said throttle lever, a foot lever for moving said flexible connection to actuate the throttle lever, the other end of 110 said flexible connection being attached to said foot lever, a hand lever, and means adjustably mounted on said flexible connection and adapted to be engaged by said hand lever whereby said flexible connection can 115 be moved independently of the foot lever.

3. In a hand and foot accelerator, a throttle lever, a cable having one end attached to said throttle lever, a foot lever to which is attached the other end of said cable, a 120 lug on said cable, a hand lever adapted to move a pulley, and means whereby the pulley moved by the hand lever will engage said lug and move said throttle lever.

4. In a hand and foot accelerator, a throttle lever adapted to open and close a throttle valve of a carburetor, a cable having one end attached to said throttle lever, a foot lever to which is attached the other end of 125 said cable, a lug adjustably mounted on said 130

cable, a pulley engaging said cable and normally contacting with said lug, whereby operation of the foot lever can move said cable to open the throttle valve without moving said pulley, a hand lever for moving said pulley to open the throttle valve, and a spring for returning the throttle valve to a closed position.

In testimony whereof, I have hereunto set my hand at Los Angeles, California, this 10 13th day of June, 1919.

WILLIAM E. CLOUGH.
